United States Patent

Des. 235,673
Patented July 1, 1975

235,673

PUZZLE TOY

Charles B. Root, Morristown, N.J., assignor to
Educational Design Associates

Filed Aug. 14, 1973, Ser. No. 388,133

Term of patent 14 years

Int. Cl. D21—01

U.S. Cl. D34—15 M

FIG. 1

FIG. 2

FIG. 3

FIG. 4

FIG. 5

FIG. 1 is a perspective view of a puzzle toy with one element in an exploded condition showing my new design;

FIG. 2 is a front perspective view thereof;

FIG. 3 is a right side elevational view thereof;

FIG. 4 is a bottom plan view thereof; and

FIG. 5 is a rear elevational view thereof.

I claim:

The ornamental design for a puzzle toy, substantially as shown.
